UNITED STATES PATENT OFFICE.

FRANK L. CROSS, OF PORT WASHINGTON, NEW YORK, ASSIGNOR TO CROSS PAPER FEEDER COMPANY, A CORPORATION OF MAINE.

SHEET-REGISTERING MECHANISM.

1,184,626.

Specification of Letters Patent. Patented May 23, 1916.

Application filed May 1, 1913. Serial No. 764,795.

To all whom it may concern:

Be it known that I, FRANK L. CROSS, a citizen of the United States, residing at Port Washington, in the county of Queens 5 and State of New York, have invented certain new and useful Improvements in Sheet-Registering Mechanisms; and I do hereby declare the following to be a full, clear, and exact description of the invention, such as 10 will enable others skilled in the art to which it appertains to make and use the same.

This invention relates to paper feeding machines and more particularly to the sheet registering mechanism of such machines.

15 The object of the invention is to provide novel and improved mechanism for securing the accurate registering of the sheets in machines in which two sheets are fed side by side to the front gages of a printing press 20 or other machine for acting on the sheets; to provide novel and improved devices for feeding the sheets against the front gages which may be used in either two sheet or single sheet feeding mechanisms; to provide 25 novel and improved means for securing the accurate register of one edge of automatically fed sheets against two spaced gages; and to otherwise improve the construction and mode of operation of the sheet registering mechanism of paper feeding machines. 30

To these ends the invention consists in the features of construction and combinations of parts hereinafter described and referred to in the claims.

35 The various features of the invention will be readily understood from an inspection of the accompanying drawings and the following detailed description of the mechanism illustrated therein.

40 In the drawings: Figure 1 is a side elevation of so much of a sheet feeding mechanism as is necessary to illustrate the application of the present improvements thereto; Figs. 2 and 2^a are a plan view of the registering devices illustrated in Fig. 1; Fig. 3 45 is a detail elevation showing one of the operating cams; Fig. 4 is a side elevation showing the devices which are arranged directly back of the front gages; Fig. 5 is a 50 sectional elevation showing the auxiliary

front gages and the devices for bringing the front edges of the sheet against the front gages of the printing press; Fig. 6 is a detail sectional plan view showing the parts illustrated in Fig. 5; Fig. 7 is a rear elevation of one of the side registering devices; Fig. 8 is a side elevation of these devices; Fig. 9 is a sectional plan view of these devices; and Fig. 10 is a sectional detail on line 10—10, Fig. 8.

60 In the drawings, the invention is illustrated as embodied in a paper feeding machine adapted to forward two sheets side by side to the front gages of a printing press. The devices for separating individual sheets from two piles or banks arranged side by side are not shown, but may consist of combing wheels and sheet controlled cutouts such as are fully illustrated in the patent to Cross, No. 812,260, February 13, 1906. 65 The sheets are advanced by the combing wheels into position between the delivery rolls 1 and the drop rolls 2 and are advanced over the supporting bars 3 and supporting tongues 4 by the delivery rolls 1 70 and their coöperating drop rolls 2, and by the forwarding rolls 5 and the coöperating drop rolls 6. The drop rolls 2 are raised and lowered in the usual manner by a cam (not shown) secured to the constantly running cam shaft 7, and the drop rolls 6 are 75 raised and lowered by a cam on the shaft engaging one end of a lever, the other end of which engages a rod 10 connected with an arm on the drop roll shaft 11, the construction being similar to that shown in Fig. 3. The delivery rolls 1 are driven by the usual mechanism similar to that shown in the above patent and the forwarding rolls 5 are driven in unison with the delivery rolls 90 through a chain 12 which passes over a wheel on the forwarding roll shaft 13, Fig. 2^a.

85 The delivery and forwarding rolls advance the sheets to auxiliary front gages 95 which are arranged somewhat back of the front gages 14 of the printing press and prevent the engagement of the front edges of the sheets with the front gages. After the sheets have been thus forwarded and arrest- 100

ed they are acted upon by side registering devices which bring the side edges of the sheets into register against two side gages, after which the sheets are advanced into register against the front gages.

Each of the side register devices preferably comprises a fixed gage and a reciprocating gripper which acts to draw the edge of the sheet against the gage. As shown, the fixed 10 gage consists of three blocks 15 secured to a base plate 16 and so arranged that the jaws 17 and 18 of the reciprocating gripper may pass between the adjacent ends of the blocks (Figs. 7 to 10). The base 16 is slotted to 15 receive the two lower jaws 7 of the gripper and is provided with a guideway for the gripper carrying slide 19. The upper jaws 18 of the gripper comprise two thin fingers pivoted to an arm 20 which is mounted upon 20 a pivot stud 21 projecting from a standard 22 on the gripper slide. The arm 20 is forced in a direction to close the gripper jaws 18 against the sheet by a spring 23. The opening and closing of the gripper is 25 controlled by a latch lever 24 pivoted to the standard 22 and provided with a roll 25 arranged to engage a recess 26 in the rearwardly projecting end of the arm 20. The lower end of the latch lever is arranged to 30 engage one or the other of two lugs 27 and 28 which are secured upon the base plate 16. When the gripper carrying slide is advanced the jaws 18 are held in raised position, as indicated in Fig. 8. As the gripper completes 35 its forward movement the lower end of the lever 24 strikes the lug 28 and disengages the roll 25 from the recess 26 so that the jaws 18 of the gripper are forced against the sheet and form two transverse creases in 40 its edge, as indicated in Fig. 10. The gripper slide is then retracted and the gripper jaws act to draw the edge of the sheet against the fixed gage blocks 15. When the edge of the sheet strikes the gage the lateral 45 movement of the sheet is arrested and the gripper jaws slide laterally along the sheet until the lower end of the latch lever 24 strikes the lug 27. Continued movement of the gripper slide then forces the latch lever 50 toward the left and the roll 25 rides up the inclined end of the arm 20, raising the arm and lifting the gripper jaws 18 into the position indicated in Fig. 8. If the edge of the sheet strikes one gage 15 before it does the 55 other, the gripper engaging that part of the edge which has not been brought against the corresponding gage 15 continues to draw the edge of the sheet toward the gage until the edge at this point is arrested by the gage. 60 At the same time the other gripper is sliding over the sheet and continuing to draw the edge at this point against the other gage 15, thus insuring the accurate register of the edge against the two spaced gages.

The base plate 16 is provided with a hub 65 which surrounds a transversely arranged supporting rod 29 and the base plate may be readily adjusted on the rod by a pinion 30 mounted on the base plate and engaging rack teeth formed on the rod. The pinion 70 is formed on a sleeve 31 mounted in a split boss 32 and provided with a knurled head 33. The base plate may be secured in adjusted position by a clamping bolt 34 which passes through the sleeve 31 and is provided with a head engaging the lower section of the boss 32. A knurled nut 35 is screwed on to the end of the clamping bolt and serves to force the head of the bolt against the lower side of the split boss, and a flange 36 80 on the sleeve 31 against the upper side of the split boss, as indicated in Fig. 7.

The base plate is held from rotation on the rod 29 by a guiding lug 37 which surrounds a rod 38. The rod 38 is mounted to 85 move longitudinally in the supporting brackets 39 and 40 and carries a collar 41 provided with a laterally projecting arm 42 arranged to fit between lugs 43 on the gripper carrying slide 19. The collar 41 is split, 90 as indicated in Fig. 7, and may be clamped in adjusted position on the rod 38 by a clamping bolt 44. When the side register devices are to be adjusted transversely of the machine the clamping bolt 44 is loosened 95 so that the collar 41 may slide on the rod 38. If the registering devices are to be thrown out of action the bolt 44 may be loosened and the collar 41 swung about the rod 38 to disengage the arm 42 from the lugs 43.

The rods 38 by which the side registering grippers are reciprocated are so connected that the side registering grippers at the opposite sides of the machine move inward and outward in unison. As shown, the inner 105 ends of the rods 38 are provided with collars 38' which have sliding engagement with the rods 29 and are connected by links 45 with the opposite ends of levers 46; the collars 38' at one side of the machine are connected to bell crank levers 47 and 48 by links 45'. The bell crank lever 47 is connected by a link 49 with one arm of a lever 50, the other arm of which carries a roll engaging a cam 51 secured to the cam shaft 7. The 110 link 49 is also connected through a link 52 with the lever 48 so that the levers 47 and 48 are moved in unison.

Each of the auxiliary front gages for positioning the front edge of the sheets preparatory to the operation of the side registering devices comprises gage fingers 53 formed on the end of a lever 54 and arranged to straddle a thin metal tongue 55 which extends forward under the path of the sheets. The lever 54 is pivoted to a bracket 56 which is adjustably secured on a transverse rod 57 arranged above the path

of the sheets. The lever is forced in a direction to hold the gage fingers 53 in the path of the sheet by a spring 58 and the position of the fingers is determined by a stop 5 screw 59 against which the rear end of the lever is held by the spring. The gage fingers 53 are arranged a short distance back of the front gages 14 and are held in the path of the sheets as they are advanced by 10 the forwarding rolls so that the advance of the sheet is arrested before its front edge reaches the front gages 14. After or during the time that the side registering devices are drawing the edges of the sheets against 15 the side gages the levers 54 are raised to withdraw the gage fingers 53 from the path of the sheet, and after the side register of the sheet has been completed the sheet is moved forward against the front gages by 20 devices which grip the front edge of the sheet and draw the sheet forward so that accurate side and front register of the sheet is insured.

The devices for gripping and drawing the sheet forward against the front gages 14 comprise rolls 60 adapted to press the sheets against the tongues 55 when the auxiliary front gages 53 are raised, and means for advancing the tongues 55 while the sheets are 25 engaged by the rolls so that the sheets gripped between the rolls and tongues are carried forward with the tongues until the front edges of the sheets strike the front gages, after which the tongues may slide 30 along the under surface of the sheets. In the construction shown, each roll 60 is carried upon an arm 61 pivotally mounted upon a stud 62 projecting from the lever 54. The arm 61 is forced in a direction to engage the roll with the tongue 55 by a torsional spring 63, the tension of which may be adjusted by adjusting the collar 64 to which one end of the spring is attached. The lever 54 and rolls 60 are alternately 40 raised and lowered through a rock shaft 65 to which a lever 66 is secured. One end of the lever is connected by a link 67 with the lever 54 and the other arm of the lever 66 is connected by a link 68 with the roll carrying arm 61. The upper end of the link 68 is connected with the lever 66 by a pin and slot connection so that the roll 60 may be free to move with relation to the arm 66 and its pressure upon the sheet will, therefore, depend upon the spring 63. The rock shaft 65 is operated at proper intervals from a cam 69 secured to the cam shaft 7 and engaging one end of a lever 70, the other end of which is connected by a link 71 to an arm 60 72 on the rock shaft.

The tongue 55 is mounted to slide in a support 73 secured to a transverse rod 74 and is reciprocated from a rock shaft 75 through an arm 76 secured to the shaft and

provided with a pin 77 engaging a vertical slot 65 formed in the carrier 78 to which the finger is secured. The rock shaft is actuated at proper intervals through a link 79, one end of which is connected to an arm 80 on the rock shaft and the other end of which 70 is engaged by a lever 80' operated by a cam 81 on the cam shaft 7, Fig. 3.

By the mechanisms described, two sheets may be advanced side by side to the registering devices, and these sheets which 75 usually have comparatively long side edges and comparatively short front edges may be quickly and accurately registered against the side gages before their front edges are brought against the front gages and then 80 drawn forward into accurate register against the front gages without disturbing the side register.

The same machine may also be used to feed single sheets to the front gages. In 85 such case all but one of the side registering devices will be disconnected or thrown out of action, two of the comber rolls and cut-outs will be thrown out of action, the auxiliary front gages will be rendered inactive, 90 and the timing of the side registering devices with relation to the devices for advancing the sheets against the front gages will be changed by changing or adjusting the cams for operating the side registering 95 devices and for depressing the rolls 60 and advancing the tongues 55. In this case the rolls 60 will be depressed and the tongues 55 advanced to draw the front edge of the sheet into accurate register against the two 100 spaced front gages 14 before the side registering device acts to draw the sheet laterally against the side gage. In this case either roll and tongue will continue to draw the edge of the sheet against the corresponding gage after the edge at that point has been arrested, and while the other roll and tongue are drawing the edge against the other front gage, in case the edge is out of alignment when advanced into position between the rolls and tongues. 105

While it is preferred to employ the specific construction and arrangement of parts shown and described, it will be understood that this construction and arrangement is not essential and may be varied and modified as is found desirable or best suited to the construction of the machine in which the invention is to be employed. 115

Having explained the nature and object 120 of the invention and specifically described one form of mechanism in which it may be embodied, what is claimed is:—

1. A sheet feeding mechanism, having, in combination, sheet forwarding devices, a front gage, means for arresting the sheet before it reaches the front gage, side registering devices acting on the arrested sheet, 125

sheet gripping devices between which the front edge of the arrested sheet lies, and means for actuating said devices to grip the sheet between them and draw it forward 5 against the front gage.

2. A sheet feeding mechanism, having, in combination, sheet forwarding devices, two side gages and coöperating devices for registering the side edge of the sheet against 10 the gages, a front gage, an auxiliary front gage to position the sheet preparatory to effecting the side register, means for withdrawing the auxiliary gage, sheet gripping devices between which the front gage of 15 the sheet lies when positioned by the auxiliary front gage, and means for actuating said devices to grip the sheet between them and draw it forward against the front gage after the side registering devices have acted.

3. A sheet feeding mechanism, having, in combination, means for forwarding two sheets side by side, two side gages outside of each sheet, outwardly moving grippers corresponding to each gage, means for actuating the grippers to grip the sheet, draw it against the gages, and thereafter slide over the sheet, front gages, and means for registering the front edges of the sheets against the front gages after the side register- 25 30 gages have released the sheets.

4. A sheet feeding mechanism, having, in combination, sheet forwarding devices, side registering devices, front gages, tongues corresponding to the front gages extending 35 forward under the path of the sheets, coöperating pressure rolls, mechanism for pressing the rolls against the tongues to grip the sheets, and mechanism for advancing the tongues to draw the sheets against the front 40 gages and thereafter slide under the sheets and for retracting the tongues.

5. A sheet feeding mechanism, having, in combination, means for forwarding two sheets side by side, side registering devices 45 for the sheets, front gages, tongues extending forward under the path of the sheets, coöperating pressure rolls, and mechanism for engaging the rolls with the sheets and for advancing the tongues after the side register- 50 55 gages have acted.

6. A sheet feeding mechanism, having, in combination, sheet forwarding devices, front gages, pressure rolls arranged to engage the front of the sheet adjacent to the front 60 65 gages, and a reciprocating tongue coöperating with each roll to grip the sheet and draw its front edge forward against the corresponding front gage.

7. A sheet feeding mechanism, having, in combination, front gages, a tongue extending forward under the path of the sheets adjacent to each gage, a pressure roll coöperating with each tongue, devices for forwarding sheets into position between the rolls and

tongues, and mechanism for forcing the rolls 65 against the tongues and for advancing and retracting the tongues.

8. A sheet feeding mechanism, having, in combination, sheet forwarding devices, a front gage, an auxiliary front gage, a tongue extending forward under the path of the sheets, a coöperating pressure roll, mechanism for removing the auxiliary gage from the path of the sheet and engaging the roll with the sheet, and means for advancing the 70 75 tongue.

9. A sheet feeding machine, having, in combination, sheet forwarding devices, a front gage, side registering devices, a reciprocating tongue extending forward under the path of the sheets, a coöperating roll, and means for pressing the roll against the sheet during the advance stroke of the tongue.

10. A sheet feeding machine, having, in combination, sheet forwarding devices, a front gage, a stationary tongue for supporting the edge of the sheet at the gage, means for arresting the sheet before it reaches the front gage, side registering devices acting 90 on the arrested sheet, and means for supporting the front of the sheet and drawing it against the front gage after the side registering devices have acted.

11. A sheet feeding machine, having, in combination, sheet forwarding devices, two side gages, a coöperating device for registering the side edge of the sheet against the gages, a front gage, a stationary tongue for supporting the edge of the sheet at the gage, 95 a single auxiliary front gage to position the sheet preparatory to effecting the side register, and means for withdrawing the auxiliary gage and drawing the sheet against the front gage by engagement with the surface 100 of the sheet near its front edge after the side registering devices have acted.

12. A sheet feeding machine, having, in combination, two spaced edge gages, a sheet gripper corresponding to each gage provided with upper and lower jaws, means for forwarding sheets into position with their edges adjacent to the gages and between the jaws of the grippers, and mechanism for actuating the grippers to grip the edge of the sheet, draw it against the gages, and to slide over the sheet after its edge is arrested by engagement with the corresponding gage.

13. A sheet feeding machine, having, in combination, two spaced edge gages, sheet gripping devices corresponding to each gage arranged to grip the edge of the sheet adjacent to the gages, mechanism for actuating the sheet gripping devices to grip the sheet, draw its edge against the gages, and slide along the sheet after its movement is arrested by engagement of its edge with the corresponding gage, and sheet forwarding

devices for forwarding the sheets into position between the gripping members of the sheet gripping devices.

14. A sheet feeding mechanism, having, in combination, two spaced edge gages, sheet gripping devices corresponding to each gage arranged to grip the edge of the sheet when presented in position with its edge adjacent to the edge gages, mechanism for actuating

the sheet gripping devices to grip the sheet to draw its edge against the gages and slide along the sheet after its movement is arrested by engagement of its edge with the corresponding gage.
